UNITED STATES PATENT OFFICE.

LOUIS BLOCK, OF MAMARONECK, NEW YORK.

GAS-COMPRESSOR.

1,239,869.

Specification of Letters Patent. Patented Sept. 11, 1917.

Application filed November 30, 1915. Serial No. 64,255.

To all whom it may concern:

Be it known that I, LOUIS BLOCK, a citizen of the United States, residing at Mamaroneck, in the county of Westchester and 5 State of New York, have invented a certain new and useful Improvement in Gas-Compressors, of which the following is a specification.

The invention relates particularly to gas 10 compressors of refrigerating machines, and especially to means for preventing the escape of gas by leakage around the piston-rod or other moving part of the mechanism. The stuffing-box usually employed for pack- 15 ing such joints is objectionable because of the friction induced when the packing is tightly compressed to seal the joint efficiently, and because of the loss of gas by leakage through the joint if the packing be 20 sufficiently relaxed to permit easy movement. Changes in temperature, wear, and other factors render it extremely difficult to maintain the packing uniformly in the required relation to the moving part.

25 The object of this invention is to eliminate the stuffing-box and provide means whereby the joint between the cylinder-head and piston-rod, or other moving part, may be effectively sealed against the escape of gas there- 30 through, with a minimum of friction between the fixed and moving parts, and to provide means for receiving and leading to the low-pressure or suction side of the compressor any gas at higher pressure penetrat- 35 ing to such joint.

The invention consists in certain novel features of construction and arrangement by which the above objects are attained, to be hereinafter described and claimed.

40 The accompanying drawings form a part of this specification and show the invention applied to several types of compressors, only such portions of the latter being illustrated as are necessary to show the relation of the 45 invention thereto.

Figure 1 is a vertical axial section of a double-acting horizontal compressor constructed in accordance with the invention.

Fig. 2 is a section on a larger scale and 50 partly in elevation, showing a detail of Fig. 1.

Fig. 3 is a section corresponding to a portion of Fig. 1 and shows a modification.

Fig. 4 is a vertical axial section showing 55 the invention applied to a single-acting vertical compressor.

Fig. 5 is a vertical central section, partly in elevation showing a pair of compressors of the single-acting inclosed type to which the invention is applied in a modified form. 60

Fig. 6 is an end view of the shaft in Fig. 5. Similar letters of reference indicate like parts in all the figures.

Referring to Figs. 1 and 2, A is the compressor cylinder having a rear head B and 65 front head C, containing a piston D arranged to be reciprocated in the cylinder as usual by a piston-rod E, and equipped with suction and delivery valves and other usual essentials, not shown.

70 On the cylinder head C is a tubular extension F flanged exteriorly at the outer end to receive a corresponding flange on a tubular piston-guide G extending inwardly, fitted to and snugly inclosing the piston-rod E 75 with liberty for the latter to reciprocate therein, and itself inclosed by the extension F but with an annular space f between these parts.

70 In the annular space f thus provided between the extension F and guide G is received a sleeve H mounted axially on the piston, surrounding the piston-rod but separated therefrom, as shown, and reciprocating with the piston.

85 Gas received in the front end of the cylinder through the suction-valve, not shown, fills the space outside the sleeve H and is compressed as usual by the forward movement of the piston but is held away from the 90 piston-rod and the joint between the latter and the guide B by the intervening sleeve. The sleeve is provided with exterior packing-rings J serving to pack the joint between the sleeve H and extension F, and any gas 95 escaping through such joint is received in the space f which is connected by a pipe K to a receiver L in communication with the suction-side of the compressor through a pipe M controlled by a checkvalve N. At 100 the bottom of the receiver is a blow-off cock R.

105 The receiver L contains gas normally at the pressure in the suction-side of the system and provides a chamber to which gas in the space f may be driven and again withdrawn by the reciprocations of the sleeve H without creating excessive changes in pressure, and insures against the formation of a vacuum in the space f. If the accumulation 110 of gas in the chamber L becomes sufficient to be compressed by the forward reciproca-

tion of the sleeve H to a pressure greater than that of the suction-side, the checkvalve N lifts and the excess escapes to the suction-side, thus maintaining the pressure in the 5 receiver L and space f at approximately that of such suction-side.

As the pressure in the space f is normally that of the suction-side of the system, the leakage of gas from such space through 10 the long close annular joint between the sleeve H and guide G, packed by the rings h, will be very small and is received in the annular space e surrounding the piston-rod E. This space is alternately increased and 15 diminished by the reciprocations of the piston, and is in communication through the passages a, b and c with a chamber d cored in the piston, containing gas at the low pressure of the suction-side and serving the 20 same function as the receiver L above described, in preventing the formation of a vacuum in the space e and in affording a compartment or recess into which any gas in the space e may be driven at each forward 25 movement of the piston:

A self-closing valve P located in the passage b is subject to the varying pressures of gas in the rear end of the cylinder, alternating from suction pressure at one end of 30 the stroke to the high pressure of delivery at the other; when the pressure in the space e and chamber d exceeds that of the suction-side, the valve P lifts and permits such excess to escape to the cylinder during the suction stroke of the piston, at which time the 35 gas in the space e is being forced into the chamber d by the approach of the piston to the end of the guide G.

Thus the pressure in the space e is held at 40 approximately that of the suction-side, and gas under delivery pressure is never in direct contact with the piston-rod nor admitted to the joint between the piston-rod and guide G. The latter is provided at each 45 end with oil grooves g aiding to prevent leakage through such joint.

As a safeguard, to be used when the compressor is idle, the flanged head of the guide G may carry a stuffingbox, as at Q in Fig. 50 3. When thus equipped the gland should be completely relaxed while the compressor is running, and tightened only when the compressor is stopped to guard against slow leakage during the idle period.

55 In the single-acting vertical compressor partially shown in Fig. 4, the hollow hub or boss of the piston D¹ provides a chamber d¹ into which leakage from the space e¹ between the piston-rod E¹ and sleeve H¹ may 60 flow and escape through the valve P¹ to the suction chamber of the compressor, and the leakage to the space f¹ between the guide G¹ and extension F¹ flows to the receiver L¹ and through the pipe M¹ past the check-valve N¹ to the suction-side. The action is

similar to that above described, and this form may if preferred be equipped with a stuffingbox as a precautionary measure to be employed when the compressor is idle.

The cubic contents of the chambers d and 70 d¹ preferably should exceed the capacity of the spaces e and e¹, and the receivers L and L¹ preferably should exceed in capacity the cubic contents of the spaces f and f¹, so that if the extensions F and F¹, guides E and 75 E¹, and sleeves H and H¹ are so proportioned as to practically fill such spaces at each reciprocation of the pistons D and D¹ the gas in such spaces may be driven into the chambers and receivers without an excessive increase of pressure, and again flow 80 to the spaces on the return stroke to avoid a vacuum therein.

In the inclosed type of compressor partially illustrated in Fig. 5 the bearing for 85 the shaft S is lengthened to form an extension F² and guide G², shown as cast integrally, and provided with an annular recess f² receiving a sleeve H² secured to and revolving with the shaft and performing the 90 same function as the sleeves H and H¹ above described. A stuffingbox Q¹ may be provided to guard against leakage when the compressor is not running.

In all the forms shown the joint between 95 the fixed parts and the moving member, whether the latter be a piston-rod as in Figs. 1 and 4 or a shaft as in Fig. 5, can never be subjected to any pressure higher than the low pressure of the suction side of the system. 100

I claim:

1. In a compressor of the character set forth, the combination of a movable member actuating a compressor piston, a fixed 105 guide inclosing such member, and means inclosing such member and guide and moving with such member in gas tight contact with said guide for excluding gas from the joint between said guide and member. 110

2. In a compressor of the character set forth, the combination of a movable member actuating a compressor piston, a fixed extension inclosing said guide and separated 115 therefrom, and a sleeve carried by such movable member and received in the space between said guide and extension in gas tight contact with said guide.

3. In a compressor, the combination of a 120 piston, a piston-rod thereon, a sleeve on said piston inclosing said piston-rod and separated therefrom, and means coacting with said sleeve for isolating said piston-rod from contact with the gas in the compressor. 125

4. In a compressor, the combination of a cylinder-head, a tubular extension thereon, a fixed guide for the latter within said extension, a piston, a piston-rod thereon, and a sleeve on said piston moving with the lat- 130

ter and inclosing said piston-rod and received between said extension and guide and matching to and received in said extension.

5. In a compressor, the combination of a cylinder-head, a tubular extension thereon, a piston, a piston-rod thereon extending axially of said extension, a tubular guide inclosing said piston-rod and carried by and separated from said extension, and a sleeve 10 on said piston inclosing said piston-rod and separated therefrom, and arranged to reciprocate in the annular space between said extension and guide.

6. In a compressor, the combination of a cylinder-head, a tubular extension thereon, a piston, a piston-rod thereon extending axially of said extension, a tubular guide inclosing said piston-rod and carried by and separated from said extension, and a sleeve 20 on said piston inclosing said piston-rod and separated therefrom, and arranged to reciprocate in the annular space between said extension and guide, and a passage leading 70 from such space to the suction-side of the 75 compressor.

7. In a compressor, the combination of a cylinder-head, a tubular extension thereon, a piston, a piston-rod thereon extending axially of said extension, a tubular guide inclosing said piston-rod and carried by and separated from said extension, a sleeve on 30 said piston inclosing said piston-rod and separated therefrom, and arranged to reciprocate in the annular space between said extension and guide, a receiver, a pipe leading 35 from such space to said receiver.

8. In a compressor, the combination of a cylinder-head, a tubular extension thereon, a piston, a piston-rod thereon extending axially of said extension, a tubular guide inclosing said piston-rod and carried by and separated from said extension, a sleeve on 40 said piston inclosing said piston-rod and separated therefrom, and arranged to reciprocate in the annular space between said extension and guide, a receiver, a pipe leading 45 from such space to said receiver, a delivery pipe leading from said receiver to the suction-side of said compressor, and a check- 50 valve in said delivery pipe.

9. In a compressor, the combination of a cylinder-head, a tubular extension thereon, a piston, a piston-rod thereon extending axially of said extension, a tubular guide inclosing said piston-rod and carried by and separated from said extension, a sleeve on 55 said piston inclosing said piston-rod and separated therefrom, and arranged to recip-

rocate in the annular space between said extension and guide, and a passage leading 60 from the space between said piston-rod and sleeve to the opposite face of said piston.

10. In a compressor, the combination of a cylinder-head, a tubular extension thereon, a piston, a piston-rod thereon extending axially of said extension, a tubular guide inclosing said piston-rod and carried by and separated from said extension, a sleeve on 65 said piston inclosing said piston-rod and separated therefrom, and arranged to reciprocate in the annular space between said extension and guide, said piston having a chamber therein and a passage leading from the space between said piston-rod and sleeve 70 to said chamber. 75

11. In a compressor, the combination of a cylinder head, a tubular extension thereon, a piston, a piston-rod thereon extending axially of said extension, a tubular guide inclosing said piston-rod and carried by and 80 separated from said extension, a sleeve on said piston inclosing said piston-rod and separated therefrom, and arranged to reciprocate in the annular space between said extension and guide, said piston having a chamber therein and a passage leading from 85 the space between said piston-rod and sleeve to said chamber, and a delivery passage from the latter to the opposite face of the piston, and a self-closing valve in said delivery passage. 90

12. In a compressor, the combination of a cylinder-head, a tubular extension thereon, a piston, a piston-rod thereon extending axially of said extension, a tubular guide inclosing said piston-rod and carried by and separated from said extension, a sleeve on 95 said piston inclosing said piston-rod and separated therefrom, and arranged to reciprocate in the annular space between said extension and guide, and packing rings on said sleeve between the latter and said extension. 100

13. In a compressor, the combination of a cylinder-head, a tubular extension thereon, a piston, a piston-rod thereon extending axially of said extension, a tubular guide inclosing said piston-rod and carried by and separated from said extension, a sleeve on 105 said piston inclosing said piston-rod and separated therefrom, and arranged to reciprocate in the annular space between said extension and guide, and packing rings on said guide between the latter and said sleeve. 110

In testimony that I claim the invention above set forth I affix my signature.

LOUIS BLOCK.
